UNITED STATES PATENT OFFICE.

ALBERT H. KARR, OF KANSAS CITY, MISSOURI.

INLAYING MACHINE.

Application filed August 31, 1923. Serial No. 660,289.

To all whom it may concern:

Be it known that I, ALBERT H. KARR, a citizen of the United States, residing at Kansas City, in the county of Jackson and State of Missouri, have invented a new and useful Inlaying Machine, of which the following is a specification.

My invention relates to inlaying machines, and the object of the invention is to provide 10 an inexpensive and highly efficient inlaying machine for cutting and routing channels in sounding boards for violins and other objects for the reception therein of reinforcing and decorative inlay members.

15 I attain this object and other advantages by means of the mechanism illustrated in the accompanying drawing in which—Figure 1, is a side elevation of an inlaying machine constructed in accordance with my invention. Figure 2, is a front elevation of the same. Figure 3, is a top plan view of the table member of the machine, taken on the line 3—3, in Figure 1, and showing the adjustable guide therein and, Figure 4, is an 20 end view of the table member apart from the machine.

Similar numerals of reference refer to corresponding parts throughout the several views.

30 Referring to the drawings—the numeral 1, designates a frame for supporting the machine elements hereinafter described. The frame has a base portion 2, a vertically extending back portion 3, and a horizontally extending arm 4, which is vertically aligned 35 with the base portion. On the front end of the base portion 2, and, likewise, on the front end of the arm 4, are forwardly extending bracket arms 5, having on their respective 40 ends bearing boxes 6, and on the ends of the brackets 5, are bearing boxes 7, which are vertically aligned with the boxes 6. The frame is adapted for mounting on a bench or other suitable supporting medium, by 45 the bolts 8, which are extended through the base of the frame. In the bearing boxes 6 and 7, on the ends of the arm 4, is revolvably mounted a shaft 9, having collars 10, thereon to support the shaft in vertical position and, also, a pulley 11, adapted for receiving an endless belt, not shown, for communicating motion to the shaft. On the lower end of the shaft 9, is secured a chuck 50 or tool holder 12, having therein a bore 55 adapted for receiving a specially designed routing tool 13, consisting of a suitable sec-

tion of a steel rod having a diameter adapted for producing a channel or groove of a predetermined width in an object subjected to its operative movement, the lower portion of 60 the tool being cut away flaring to produce a face 14 and cutting edges 15, which tool is detained in the chuck by a set screw 16, in the well known manner. A plunger rod 17, is slidably mounted in the boxes 6 and 7, 65 on the end of the base 1, the lower end of the rod being pivotally mounted on a foot lever 18, the latter being pivoted at its inner end to a suitable supporting medium, not shown. On the rod 17, is mounted a concentric stop 70 19 and encircling the portion of the rod between the stop 19 and the box 6, on the end of the base, is mounted a spiral spring 20, which normally presses upward on the stop 19, to thereby hold the stop against the lower 75 side of the box 7, on the end of the bracket associated with the end of the base of the frame. On the upper end of the rod is mounted a table member 21, having on the under side thereof a boss 22, which is penetrated by the plunger rod and held in place 80 therein by means of a set screw 23. An elongated slide bearing 24, is formed in the upper side of the table and the bearing adapted for slidably receiving a slide member 25. The slide member is provided with 85 a set screw 26, which is adapted for impinging on the bottom of the bearing to thereby hold the slide member adjustable in the bearing. Adjacent the inner end of the slide member, on the upper side thereof, is rigidly mounted a guide post 27.

The guide 27, is especially designed in contour to have a concentrically formed portion and as shown at 28, and an eccentric 90 portion, as shown at 29, for a purpose that will hereinafter appear.

The machine above described is adapted for the inlaying of reinforcing or decorative material, as for instance, in the upper 100 side of the sounding board of a violin to prevent the checking of the same. To operate the machine the foot lever is pressed down against the tension of the spring 20, thereby the plunger rod is drawn down, 105 carrying with it the table 21, whereupon the material to be treated, for instance a violin sounding board, is laid upon the table with its upper side presented to the tool 13, the edge of the board being held against the eccentric portion 29 of the guide post 27. The pressure on the foot lever is then re-

moved and the spring 20 reacts to return the plunger rod 19, and the table thereon, back to normal position, and thus bringing the upper side of the sounding board to the point of the tool, the latter being in motion penetrates the board to the pre-determined depth of the proposed channel. The shaft 9, being driven, the tool is spinning and the cutting edges 14 and 15 thereon effect a clean cutting of the channel. After the tool has penetrated the board the operator pushes the board inward and, as the edge of the board is continually bearing upon the eccentric portion of the guide post, the channel formed is of a uniform width and uniformly spaced from the edge of the board. The eccentric portion of the guide post permits the operator to rout the channel along straight or curved lines in the one operation, as in the case of the violin sounding board, where straight and curved lines are involved in routing a channel for inlaying material. If it is desired to have the channel at a lesser distance from the edge of the board, the slide 25, is moved inwardly a suitable distance and held there by the set screw 26. If a greater distance from the edge of the board is desired, the slide 25, is moved outwardly a suitable distance and there set to place by the screw 26. The relative adjustment of the tool 13, with the table 21, deter-

mines the depth of the channel. The relative adjustment of the table and the tool may be obtained by sliding the tool in the chuck, or, by sliding the table on the plunger rod 17, or, by both. The adjustment of the tool to determine the depth of the channel requires that the table be lowered sufficiently to permit the operator to place the board under the tool and again against the guide post and, to accomplish this action, the foot pedal is pressed down, as before explained.

Having described my invention what I claim is—

In an inlaying machine, the combination, of a frame, a shaft revolvably mounted in said frame, a channelling tool actuated by said shaft, a plunger rod slidably mounted on said frame and aligned with said shaft, a pivoted lever pivotally connected to one end of said rod, a table adjustably connected to the other end of said rod, yielding means mounted on said rod to normally hold said table in elevated position, and a guide slidably and adjustably mounted on said table, said guide having an eccentric face constantly presented to said tool.

Kansas City, Missouri, August 23rd, 1923.

ALBERT H. KARR.
